The ornamental design for a tire sidewall, as shown and described.

DESCRIPTION

FIG. 1 is a right side perspective view of a tire sidewall showing our new design;

FIG. 2 is a left side perspective view thereof;

FIG. 3 is a right side elevational view thereof; and,

FIG. 4 is a left side elevational view thereof.

In the drawings, the broken lines showing of the tire tread, inner bead and the peripheral boundary between the tire tread and the sidewall in FIGS. 1 through 4 depict environmental subject matter and form no part of the claimed design.
